DESIGN FOR A COMBINED BATTERY TESTER AND CHARGER

John D. Maultsby, Jr., Kansas City, Mo., assignor
to C. Earl Hovey, trustee, Kansas City, Mo.

Application March 3, 1945, Serial No. 118,240

Term of patent 7 years

(Cl. D26—5)

To all whom it may concern:

Be it known that I, John D. Maultsby, Jr., a citizen of the United States, residing at Kansas City, in the county of Jackson and State of Missouri, have invented a new, original, and ornamental Design for a Combined Battery Tester and Charger, of which the following is a specification, reference being had to the accompanying drawing, forming a part thereof.

Fig. 1 is a perspective view of the combined battery tester and charger, showing my new design.

Fig. 2 is a side elevational view thereof; and
Fig. 3 is a top plan view thereof.

I claim:

The ornamental design for a combined battery tester and charger, as shown.
